AIR-FEED-CONTROLLING DEVICE

Application filed September 30, 1927. Serial No. 223,039.

This invention relates to fluid actuated rock drills, but more particularly to an air feed controlling device for rock drills of the stoper type.

3 The objects of the invention are to regulate the pressure in the air feeding element of the drill in an improved and simplified manner and to economize in the pressure fluid consumption of the feeding element.

10 The foregoing objects are attained in the present instance by means of a fluid actuated valve which, in one of its position, may form a part of the exhaust passage through which pressure fluid is exhausted from the feeding element. When in that position the valve may also serve to prevent the admission of pressure fluid into the feeding element until the pressure therein has dropped to a value sufficiently low to prevent an unduly rapid 15 advance of the drill towards the work whenever conditions in the drill hole are such that the best drilling results may be obtained by applying only a light pressure to the working implement.

20 Other objects will be in part obvious and in part pointed out hereinafter.

The invention consists of the combination of elements and arrangement of parts having the general mode of operation substantially 25 as hereinafter described and claimed and illustrated in the accompanying drawing, in which the figure illustrates a portion of a stoper type rock drill in vertical section having the invention applied thereto.

30 Referring more particularly to the drawing, A designates a percussive cylinder in which is disposed a reciprocatory hammer piston B for delivering blows of impact to a working implement such as a drill steel (not shown). A closure is provided for the 35 rearward end of the cylinder A in the form of a back cylinder washer C which has a flat surface D at its rearward end to form a seat for an oscillatory plate valve E. The plate 40 valve E may be of a well known type and

in this instance is disposed about a rifle bar F which interlocks slidably with the piston B in the usual manner for imparting rotary movement to the working implement.

45 Seated on the flat surface D of the back cylinder washer C is a back head G which encircles the rifle bar F and is recessed to form a valve chamber H for the reception of the valve E. In addition to the functions described the back head G also acts as a seat 50 for one end of a rifle bar head J wherein are disposed the usual pawl devices K adapted to cooperate with a toothed rotation ratchet L seated on the back head G.

55 The rifle bar F in this instance is held 60 against movement in a rearward direction by a head block O which is seated on the rearward end of the rotation ratchet L and has a reduced flanged portion P which extends into the rotation ratchet L, both for centralizing the head block with respect to the rotation ratchet and also to act as an abutment for the head J of the rifle bar F.

65 A throttle valve Q, preferably of the rotatable type is disposed in the head block O and 70 has a lever R whereby said throttle valve may be manipulated. A bore S in the throttle valve Q may be in constant communication with a source of pressure fluid supply as is customary in devices of this type, and such 75 pressure fluid may be conveyed to the valve chamber H through a port T in the throttle valve and passage U wherewith the port registers, said passage U being formed in the head block O, the rotation ratchet L and in the 80 back head G.

85 The pressure fluid admitted into the valve chamber H is distributed by the valve E and flows to the rearward and front ends of the cylinder through inlet passages V and W 85 respectively.

90 The feeding element for advancing the rock drill towards the work in this instance comprises a feeding cylinder X and a feed piston Y disposed in the cylinder X. The

feed piston Y may be of a well known type in which a piston head Z is disposed on a rod b and in which the rod extends slidably through the front end of the feed piston to rest against a suitable support such as the floor of a mine or other suitable supporting means.

The feeding cylinder X in this instance is centralized with respect to the head block O by means of the bushing c which extends into both the cylinder X and the head block O and has a central aperture d to receive a nut e screwed on the end of the rod b for holding the head Z thereon.

In accordance with the present invention, the throttle valve Q is provided with a port f which, in the open position of the throttle valve, registers with an inlet passage g in the head block O for conveying pressure fluid to the feeding cylinder X. In the present instance the inlet passage g terminates in a valve chamber h formed in the head block O and a passage j affords communication between the valve chamber h and the feeding cylinder X.

Preferably a second passage k is formed in the head block O for exhausting pressure fluid from the feeding cylinder X into the valve chamber h, said passage k opening in this instance into the valve chamber h at the lowermost end of the said valve chamber.

At the opposite end of the valve chamber h is an exhaust passage o which leads through the rotation ratchet L, the back head G and the back cylinder washer C and preferably terminates at point in the cylinder A where it registers with a passage p in a rotation handle q. The rotation handle q in this instance projects through an aperture r in the cylinder A and is clamped in position by a nut s screwed on the end of said rotation handle.

Suitable means are provided for controlling the exhaust of pressure fluid from the feeding cylinder. The means in the present instance consist of a relief valve t preferably seated in a bushing u disposed in the outermost or free end of the rotation handle q. The relief valve t is preferably normally held closed by a spring v which is seated with one end against the relief valve t and with its other end against a spring seat w disposed at the innermost end of the bushing u. A stem x carried by the relief valve t extends slidably into a bore y in the bushing u and has a reduced neck portion z to permit the passage of pressure fluid around the stem x to ports 2 in the bushing u opening into an external groove 3 in the bushing u. The groove 3 may be of a suitable length to register with a passage 4 in a grip portion 5 of the rotation handle q.

The relief valve t, as will be observed, is of the reciprocable type and the means whereby said relief valve may be unseated consist in this instance of a push rod 6 having an in-

termediate head 7 slidable in a recess 8 in the outermost end of the bushing u, and an inner reduced projection 9 which extends into the bore y and normally abuts the end of the valve stem x.

The push rod 6 may be of a length to extend beyond the end of the rotation handle q, the outer end 10 of said push rod being of somewhat smaller diameter than the head 7 and carrying a button 11 conveniently situated to enable the operator to manipulate the button 11 with the same hand wherewith he grasps the grip portion 5 of the rotation handle q. The bushing u and the push rod 6 are held in operative position by a hollow threaded plug 12 screwed in the outer end of the rotation handle q.

Disposed in the valve chamber h is a feed valve 13 which has a recess 14 for the reception of a spring 15 whereby the valve 13 is normally held in the lowermost end of the valve chest h. In the lowermost end of the valve 13 is formed a port 16 and this port 16 forms the restricted portion of the path provided for the escape of pressure fluid from the feeding cylinder X to control the volume of pressure fluid which may be exhausted from said feeding cylinder.

In the periphery of the valve 13 is formed an annular groove 17 which normally affords communication between the passages g and j for admitting pressure fluid into the feeding cylinder X.

In the drawing, the air feeding controlling means are shown in the positions which they will assume when the air feeding cylinder X is exposed to line pressure. Under these conditions, the throttle valve t will remain closed and the valve 13 will occupy its lowermost position in the valve chest h to admit pressure fluid through the passages g and j and the annular groove 17 into the feeding cylinder for advancing the drill towards the work.

During normal drilling the spring 15 will hold the valve 13 in the position described. If, however, as occasionally happens in drilling operations, the working implement encounters either a soft or an unusually hard strata in the material being drilled, in either case of which it is desirable to reduce the pressure against the working implement and at the same time continue the normal reciprocations of the piston B, the attendant may press against the button 11 to unseat the throttle valve t. In this way the pressure fluid in the passages between the valve 13 and the relief valve t may be released so that momentarily there will be no pressure acting on the uppermost end of the valve 13 other than that of the spring 15. Owing to the fact that the passage k opens directly against the lowermost end of the valve 13 pressure fluid from the feeding cylinder X will act against the said valve and move it

to its uppermost position in the valve chest h . In this position of the valve 13 the annular groove 17 will be moved out of registry with the passage j , thus cutting off the supply of pressure fluid into the feeding cylinder X and with the relief valve t in its open position pressure fluid may escape through the passage k , the restricted port 16, thence through the recess 14 and the exhaust passages leading therefrom through the rotation handle to the atmosphere.

When conditions in the drill hole again permit the application of a greater pressure to the working implement the button 11 may be released and the throttle valve t will then be closed by the spring v . Immediately upon the closing of the throttle valve t pressure fluid will flow from the feeding cylinder through the port 16 into the upper end of the valve chest h . Both ends of the valve 13 will then be constantly exposed to pressure fluid of the same pressure and the spring 15 will then move the valve 13 to its initial position, thus again opening communication between the passages g and j for the admission of pressure fluid into the feeding cylinder X .

The present invention has been found to effect a considerable economy in the matter of pressure fluid required for actuating the feeding element, since, whenever it is desired to reduce the pressure in the feeding element the supply thereto is also simultaneously cut off, thus eliminating the necessity of constantly exhausting a greater amount of pressure fluid from the feeding cylinder than is being admitted thereto.

I claim:

1. In an air feed controlling device for rock drills, the combination of a percussive cylinder and an air feeding cylinder, a head block between the cylinders having an inlet passage for conveying pressure fluid to the air feeding cylinder, an exhaust passage leading from the air feeding cylinder to the atmosphere, and a valve controlling the passages normally exposed at both ends to the pressure fluid of the same pressure, said valve being normally open to admit pressure fluid from a source of supply through the inlet passage into the feeding cylinder and adapted to normally remain open.

2. In an air feed controlling device for rock drills, the combination of a percussive cylinder and an air feeding cylinder, a head block between the cylinders having an inlet passage for conveying pressure fluid to the air feeding cylinder, an exhaust passage leading from the air feeding cylinder to the atmosphere, a valve controlling the passages exposed at both ends to pressure fluid whereby said valve is actuated to close the inlet passage and open the exhaust passage upon a reduction of pressure on one end of the valve, and a spring acting on the valve to

hold said valve normally in a position where-in pressure fluid may constantly flow from the inlet passage into the air feeding cylinder.

3. In an air feed controlling device for rock drills, the combination of a percussive cylinder and an air feeding cylinder, a head block between the cylinders having an inlet passage for conveying pressure fluid to the air feeding cylinder, an exhaust passage leading from the air feeding cylinder to the atmosphere, a valve controlling the passages and constantly exposed at both ends to pressure fluid from the feeding cylinder, a spring acting against one end of the valve augmenting the pressure fluid acting thereon to overcome the pressure against the opposite end of the valve, and means controlling the outlet opening of the exhaust passage for exhausting pressure fluid from one end of the valve, thus enabling the pressure fluid at the other end of the valve to actuate the valve into a position for cutting off communication between the inlet passage and the feeding cylinder and for permitting the exhaust of pressure fluid from the feeding cylinder through the exhaust passage to the atmosphere.

4. In an air feed controlling device for rock drills, the combination of a percussive cylinder and an air feeding cylinder, a head block between the cylinders having an inlet passage for conveying pressure fluid to the air feeding cylinder, an exhaust passage leading from the air feeding cylinder to the atmosphere, a valve controlling the passages exposed at both ends to pressure fluid from the air feeding cylinder, a spring acting against one end of the valve augmenting the pressure fluid acting thereon to overcome the pressure acting against the opposite end of the valve, and manually operable means controlling the outlet opening of the exhaust passage for exhausting pressure fluid from one end of the valve, thus enabling the pressure fluid at the other end of the valve to actuate the valve into a position for cutting off communication between the inlet passage and the feeding cylinder and for permitting the exhaust of pressure fluid from the feeding cylinder through the exhaust passage to the atmosphere.

5. In an air feed controlling device for rock drills, the combination of a percussive cylinder and an air feeding cylinder, a head block between the cylinders having an inlet passage for conveying pressure fluid to the air feeding cylinder, an exhaust passage for the feeding cylinder, a valve controlling the passages exposed at both ends to pressure fluid from the air feeding cylinder, said valve having a port to control the volume of pressure fluid exhausting from the air feeding cylinder into the exhaust passage, a spring acting against one end of the valve augmenting the

pressure fluid acting thereon to overcome the pressure acting against the opposite end of the valve, and manually operable means controlling the outlet opening of the exhaust passage for exhausting the pressure fluid acting against one end of the valve, thus enabling the pressure fluid acting against the other end of the valve to actuate the valve into a position for cutting off communication between the inlet passage and the feeding cylinder and for permitting the exhaust of pressure fluid from the feeding cylinder through the port and the exhaust passage to the atmosphere.

6. In an air feed controlling device for rock drills, the combination of a percussive cylinder and an air feeding cylinder, a head block between the cylinders having an inlet passage for conveying pressure fluid to the air feeding cylinder, an exhaust passage for the feeding cylinder, a feed valve controlling the passages exposed at both ends to pressure fluid from the air feeding cylinder, said valve having a port to control the volume of pressure fluid exhausting from the air feeding cylinder into the exhaust passage, a spring acting against one end of the valve augmenting the pressure fluid acting thereon to overcome the pressure acting against the opposite end of the valve, a rotation handle secured to the drill having a passage registering with the exhaust passage, a relief valve in the rotation handle controlling the exhaust passage, and a manually operable push rod for opening the relief valve to exhaust pressure fluid acting against one end of the feed valve, thus enabling the pressure fluid acting against the other end of the valve to actuate the feed valve into a position for cutting off communication between the inlet passage and the feeding cylinder and for simultaneously permitting the escape of pressure fluid from the feeding cylinder through the port and the exhaust passage to the atmosphere.

7. In an air feed controlling device for rock drills, the combination of a percussive cylinder and an air feeding cylinder, a head block between the cylinders having an inlet passage for conveying pressure fluid to the air feeding cylinder, an exhaust passage for the feeding cylinder, a feed valve controlling the passages exposed at both ends to pressure fluid from the air feeding cylinder, said valve having a port to control the volume of pressure fluid exhausting from the air feeding cylinder into the exhaust passage, a spring acting against one end of the valve augmenting the pressure fluid acting thereon to overcome the pressure acting against the opposite end of the valve, a rotation handle secured to the drill having a passage, a spring pressed relief valve in the free end of the rotation handle controlling the exhaust passage, and a manually operable push rod for opening the relief valve to exhaust pressure fluid acting against one end of the feed valve,

thus enabling the pressure fluid acting against the other end of the feed valve to actuate the feed valve into a position for cutting off communication between the inlet passage and the feeding cylinder and for simultaneously permitting the escape of pressure fluid from the feeding cylinder through the port and the exhaust passage to the atmosphere.

8. In testimony whereof I have signed this specification.
